UNITED STATES PATENT OFFICE.

KNIGHT H. THOMPSON, OF SHELBY, OHIO, ASSIGNOR TO DAVID W. CUMMINS, OF SHELBY, OHIO.

DESIGN FOR A VEHICLE-LAMP.

45,545.

Specification for Design.

Patented Mar. 31, 1914.

Application filed January 30, 1914. Serial No. 815,555. Term of patent 14 years.

To all whom it may concern:

Be it known that I, KNIGHT H. THOMPSON, a citizen of the United States of America, residing at Shelby, in the county of Richland and State of Ohio, have invented a new, original, and ornamental Design for a Vehicle-Lamp, of which the following is a specification, reference being had to the accompanying drawing, forming part thereof.

is a view in elevation of a vehicle lamp embodying my invention. Fig. 2 is a top plan view of the same.

What I claim is,—

The ornamental design for a vehicle lamp, as shown.

KNIGHT H. THOMPSON.
